MERCURY SWITCH

Robert Warren Allison, Atlanta, Ga.

Application September 7, 1943, Serial No. 501,464

5 Claims. (Cl. 200—33)

This invention relates to an improved form of mercury switch, in which an accurate time delay is obtained between the tilting of the switch and the time the electrical contact is made, or broken, as the case may be.

Mercury switches are well known, and heretofore it has been proposed to so construct such switches that there is a time delay in the opening, or closing, of the electrical circuit. However, such switches either have been entirely inoperative, or somewhat less than satisfactory in operation, due to the fact that they either simply trapped the mercury in one end of the mercury tube of the switch and attempted to control its flow to the other end of the tube by restricting its flow through a small orifice, or depended upon the force exerted by the weight of the column of mercury to force a portion thereof through an orifice or restricted passage.

Those prior switches which depended solely upon the delay being caused by restricting the flow of the mercury through a small orifice, were inoperative as the molecular attraction, or surface tension, of mercury is so high that it prevented the mercury from flowing through a small orifice. If the orifice were made large enough so that the molecular attraction of the mercury did not too seriously interfere with the flow of mercury therethrough, the desired delay in opening, or closing, the switch was not obtained.

The molecular attraction, or surface tension, of mercury is so great that it will support a column of mercury of about three-fourths of an inch in height over an opening of such size as to cause any appreciable delayed action in a mercury switch. Hence, in those prior switches in which the force exerted by the weight of a column of mercury was utilized to force a portion of the mercury through a small orifice, such a large quantity of mercury was necessary to make the switch operative as to require the switch to be of impractical length to produce even a short delayed action, as the mercury would cease to flow through the restricted orifice, or passage, as soon as the force exerted by the hydrostatic head of the mercury decreased to an extent such that it became equal to the molecular attraction of the mercury over the opening. Thus, a substantial column of the mercury always was left in the upper end of the mercury tube. Furthermore, such switches were objectionable in that the hydrostatic head of the mercury caused the mercury which did pass through the restricted orifice, or passage, to flow therethrough too rapidly and the electric circuit to be opened, or

closed, too soon. My experiments have indicated that to obtain a delay in the opening, or closing, of the electrical circuit as short as 15 seconds in such prior switches, a column of mercury of the order of four or five inches in height and one-fourth inch in diameter is necessary.

In accordance with my invention, there is provided a mercury switch in which the disadvantages of the prior mercury switches, as set forth above, are overcome, and a mercury switch is provided which is not of excessive length and which will give an accurate time delay between the tilting of the switch and the time the electrical circuit is opened, or closed.

15 In mercury switches constructed as herein-after set forth, the force exerted by the molecular attraction of the mercury which normally would prevent the mercury from flowing through a small orifice, or restricted passage, is equalized, 20 and even used to facilitate the flow of the mercury through the orifice, or passage, thus enabling the desired time delay to be accomplished in a switch of relatively small size. As a matter of fact, a mercury switch about one inch long 25 and three-eighths inch in diameter, and constructed in accordance with my invention, can have a predetermined time delay period of anywhere from a few seconds to two minutes.

More specifically, my invention comprises a 30 mercury switch in which mercury is caused to flow through a restricted orifice, or passage, from one end to the other of a tube of insulating material, as in prior mercury switches. However, the switch is so constructed and arranged that a pool of mercury is maintained at all times on both sides of the restricted orifice, or passage, regardless of the position to which the switch may be tilted in operation, and the orifice is formed at the end of a relatively long tapering passage or nozzle. The amount of mercury in the switch is such that the passage or nozzle always is submerged in the mercury so that no air can enter thereinto. Thus, the molecular attraction of the mercury always tends to draw the mercury into the pool at each side of the restricted orifice, but the force is not sufficiently great to break the mercury apart in the restricted orifice and form a vacuum. A force equal to that 40 exerted by a column of mercury 28 inches in length would be necessary to do that, and, of course, the molecular attraction of mercury is not that great. Thus, when the switch is tilted in the direction to cause a flow of mercury through the tapering passage toward the restricted orifice at the end thereof, the "pull" of

the mercury already in the lower pool, plus the slight force exerted by the hydrostatic head of the mercury in the upper pool, is greater than the molecular "pull" of the mercury in the upper pool, and the mercury will flow freely through the restricted orifice from the upper pool to the lower pool. The size of the restricted orifice at the end of the tapering passage is predetermined to so control the flow as to give the desired time delay before the electric circuit is opened, or closed.

The invention will be further described in connection with the accompanying drawing, but it is to be understood that such further disclosure is by way of exemplification and that the invention is not limited thereby.

In the drawing:

Fig. 1 is a longitudinal sectional view through a mercury switch embodying the present invention, and adapted to give a substantially instantaneous closing of the electrical circuit and a time delay between the tilting of the switch to its "off" position and the time the electrical circuit is broken, with the switch being shown in its full "on" position;

Fig. 2 is a longitudinal sectional view through the switch shown in Fig. 1, with the switch being in its full "off" position;

Fig. 3 is a view similar to Fig. 2, but showing the switch with the mercury passing through the restricted orifice from the upper pool to the lower pool after the switch has been tilted to its "off" position and prior to the breaking of the circuit between the electrical contacts;

Fig. 4 is a longitudinal sectional view through a mercury switch embodying the present invention, and constructed to give a substantially instantaneous opening of the electrical circuit and a time delay between the tilting of the switch to the "on" position and the time the contact between the electric circuit is made, with the switch being shown in its full "off" position;

Fig. 5 is a longitudinal sectional view of the mercury switch in Fig. 4, with the switch being shown in its full "on" position; and

Fig. 6 is a longitudinal sectional view similar to Fig. 5, but showing the switch with the mercury passing through the restricted orifice from the upper pool to the lower pool during the time elapsing between the tilting of the switch to its "on" position and the bridging of the electrical contacts by the mercury.

It is apparent that the switch may be constructed to give either a substantially instantaneous bridging of the electrical contacts to close the electric circuit, and a delay between the time the switch is tilted to its "off" position and the opening of the electrical circuit, or a substantially instantaneous opening of the electrical circuit and a delay between the time the switch is tilted to its "on" position and the time the mercury bridges the electrical contacts to close the circuit.

A switch constructed to give a substantially instantaneous closing of the electrical circuit and a delay on the opening of the electrical circuit is shown in Figs. 1, 2 and 3. Referring to those figures, the switch comprises a tube 1 of any suitable material, such as glass, or other insulating material, mounted to be tilted between its "on" and "off" positions. The means for tilting the switch form no part of the present invention and are not shown. When constructed of glass, the tube, after assembly of the several parts of the switch, may be flame-sealed, or the tube may be of the open-ended type and have its open end

hermetically sealed with sealing wax or other insulating material 2.

5 A funnel-shaped baffle 3 having a spout 4 of relatively large diameter extending from its smaller end, is secured across the tube 1 substantially midway of its length. The baffle may be of metal or other material having its outer perimeter cemented or otherwise secured to the wall of the tube, or it may be formed integrally with the tube.

10 A pair of electrical contacts 5 and 6 extend through the insulating sealing material 2, and have their ends positioned relatively close to the baffle 3.

15 At one side, close to the perimeter thereof, the baffle 3 is provided with an elongated tapering passage or nozzle 7 which terminates in a small orifice 8. The passage or nozzle 7 extends from the baffle 3 at the side thereof opposite the electrical contacts 5 and 6. The tube is approximately one-half filled with mercury and, when the tube is tilted in one direction, the mercury is adapted to submerge the electrical contacts 5 and 6 and close the electric circuit of which they form a part. When the tube is tilted in the opposite direction, the mercury will flow away from the electrical contacts and open or break the electric circuit.

20 The space within the tube 1 which is not filled with mercury, is filled with nitrogen or some other 30 inert gas, so that corrosion of the contacts will not occur.

25 The passage or nozzle 7 extends to near the proximate end of the tube 1 and tapers to the orifice 8, which is of a size to sufficiently restrict the flow of mercury therethrough to give the desired time delay between the tilting of the switch to the "off" position, shown in Figs. 2 and 3, and the time the electrical circuit is opened by failure of the mercury any longer to bridge the contacts 40 5 and 6.

30 The amount of mercury in the tube is sufficient to maintain the passage or nozzle 7 filled at all times, regardless of whether the switch is in the "on" position shown in Fig. 1, or the "off" position shown in Figs. 2 and 3, so that the gas within the tube never enters the nozzle to interfere with the flow of mercury through the restricted orifice 8.

35 With the switch in the "on" position shown in Fig. 1, the electrical contacts are submerged in the mercury at the upper end of the tube, at the right hand side of the baffle 3, with the result that the electrical circuit of which the contacts 5 and 6 are a part, is closed. Also, when the 45 switch is in that position, a substantial amount of the mercury is at the lower end of the tube, at the left hand side of the baffle 3, and submerges the nozzle 7.

40 If the switch is now turned to its upright or "off" position shown in Figs. 2 and 3, a large portion of the mercury is trapped above the baffle and is prevented by the spout 4 from passing therethrough, except through the restricted orifice 8. When the tube is first tilted to such position, the contacts 5 and 6 are still well submerged in the mercury and the electrical circuit remains closed. Also, the lower end of the passage or nozzle, having the restricted orifice 8 at its end, is submerged in the mercury in the pool at the 55 bottom of the tube, so that the molecular attraction of the mercury in the lower pool tends to draw the mercury from the upper pool through the orifice 8. The force exerted by the hydrostatic head of the mercury in the upper pool also tends 60 to force the mercury through the restricted ori-

65 fice 8. The mercury in the upper pool is forced through the restricted orifice 8 and passes into the passage or nozzle 7, and continues to do so until the mercury has been 70 removed from the electrical contacts 5 and 6. The mercury is then removed from the tube 1, and the tube is tilted back to its "on" position, so that the mercury again 75 fills the tube 1 and submerges the contacts 5 and 6.

fice 8, and as the combination of the force exerted by the hydrostatic head of the mercury in the upper pool and the force exerted by the molecular attraction of the mercury in the lower pool, is greater than the molecular attraction of the mercury in the upper pool, the mercury readily passes through the orifice, even when the orifice is made very small. After the desired time, predetermined by the size of the orifice 8, the level of the mercury in the upper pool will have dropped to a position below the level of the electrical contacts 5 and 6 and the electrical circuit thereby broken. Such a condition is shown in Fig. 2. However, even when the mercury has reached its lowermost level, a portion 10 thereof still will remain on the upper side of the baffle 3, above the uppermost part of the nozzle 1, so that none of the gas within the tube can enter the nozzle.

If the switch is now tilted back to its "on" position, shown in Fig. 1, the mercury quickly spills through the spout 4 of the funnel-shaped baffle 3, and almost instantaneously closes the electrical circuit by bridging the contacts 5 and 6.

The switch shown in Figs. 4, 5 and 6, is constructed to give a substantially instantaneous opening of the electrical circuit, and a time delay between the tilting of the switch to "on" position and the time the electrical switch is closed. In the switch of those figures the passage or nozzle 1' extends into the end of the mercury tube 1 containing the electrical contacts 5' and 6', and the electrical contact 5' extends through a thickened portion 1^a of the tube and enters the interior of the tube at a point near the baffle 3', while the contact 6' extends through the insulating sealing material 2' at a point opposite the thickened portion 1^a of the tube, and terminates close to the insulating sealing material. Otherwise, the construction of the switch shown in Figs. 4, 5 and 6 is the same as the construction of the switch shown in Figs. 1, 2 and 3, and the same reference characters, primed, are used to designate similar parts.

With the switch of Figs. 4, 5 and 6 in the position shown in Fig. 5, the electrical contact 6', which extends through the insulating sealing material at one side of the tube, is submerged in the mercury, but the electrical circuit is still broken as the electrical contact 5' is at the top of the tube, away from the mercury.

When the switch is tilted from the "off" position shown in Fig. 4 to the "on" position shown in Figs. 5 and 6, a large portion of the mercury is trapped above the baffle 3' by the spout 4', and can only pass to the bottom of the pool through the passage or nozzle 1' and the restricted orifice 8' at the bottom thereof. The condition of the switch just after being tilted to its "on" position, and before the electrical circuit has been completed by the mercury submerging the electrical contact 6', as well as electrical contact 5', is shown in Fig. 6. After a predetermined time, determined by the size of the orifice 8', most of the mercury will have flowed from the upper pool to the lower pool and submerged the contact 5' in the upper part of the lower portion of the tube, as well as the contact 6', with the result that the electrical circuit then is closed. The condition of the switch at such a time is shown in Fig. 5. However, even after the flow of mercury from the upper portion of the tube to the lower portion thereof has stopped, a portion 10' thereof will remain above the baffle 3' and above the top of the nozzle or passage 1', so that none of the gas in the tube can enter the passage or

nozzle to interfere with the flow of mercury through the orifice 8' at the end thereof. It will also be noted that in the switch of these figures, like in the switch of Figs. 1, 2 and 3, the passage or nozzle 1' and the orifice 8' at the end thereof are completely submerged in the mercury at all times, regardless of which of its positions the switch is tilted.

If desired, one or both of the electrical contacts 5 and 6 of the switch of Figures 1, 2 and 3, or the electrical contact 5' of Figs. 4, 5 and 6, may be arranged to be adjustable longitudinally of the tube, so that the time delay between the opening or closing of the electrical circuit, as the case may be, may be varied for a switch having any size restricted orifice for the passage of the mercury from one end of the tube to the other.

From the foregoing it will be readily understood that a switch constructed in accordance with the present invention will give an accurate predetermined time delay between the time the switch is tilted to open, or close, the electrical circuit, and the time the electrical circuit actually is opened, or closed, depending upon the size of the restricted orifice through which the mercury passes, due to the fact that the passage or nozzle having the restricted orifice at the end thereof, is at all times completely submerged in the mercury within the tube, thus preventing the molecular attraction of the mercury from interfering with the free flow of the mercury through the restricted passage, even when the restricted passage is made quite small. It will also be understood that by varying the size of the restricted orifice at the end of the tapering passage or nozzle, the period of delay in the opening, or closing, of the electrical circuit may be varied over a substantial period of time.

What I claim is:

40. 1. A delayed-action mercury switch comprising a tube adapted to be tilted to "on" and "off" positions, a baffle in said tube intermediate the length thereof, a pair of electrical contacts in the tube at one side of said baffle, a body of mercury in the tube adapted upon tilting of the tube to make and break an electric circuit including said electrical contacts, the baffle being adapted to trap a portion of the body of mercury when the tube is tilted to one of its positions, and an elongated tapering nozzle extending from the baffle into one end of the tube, said nozzle forming a passage from one side of the baffle to the other for mercury trapped by the baffle when the tube is tilted to one of its positions, said nozzle terminating at its distal end in a restricted orifice, the mercury in the tube completely filling the nozzle and submerging the restricted orifice at all times, regardless of whether the tube is in its "on" or "off" position.
45. 2. A delayed-action mercury switch comprising a tube adapted to be tilted to "on" and "off" positions, a baffle in said tube intermediate the length thereof, a pair of electrical contacts in the tube at one side of said baffle, a body of mercury in the tube adapted upon tilting of the tube to make and break an electric circuit including said electrical contacts, the baffle being adapted to trap a portion of the body of mercury when the tube is tilted to one of its positions, and an elongated tapering nozzle extending from the baffle, adjacent the periphery thereof, into one end of the tube, said nozzle forming a passage from one side of the baffle to the other for mercury trapped by the baffle when the tube is tilted to one of its positions, said nozzle terminating at its distal end in

a restricted orifice, the mercury in the tube completely filling the nozzle and submerging the restricted orifice at all times, regardless of whether the tube is in its "on" or "off" position.

3. A delayed-action mercury switch comprising a tube adapted to be tilted to "on" and "off" positions, a funnel-shaped baffle extending across said tube intermediate the length thereof, a pair of electrical contacts in the tube at one side of said baffle, a body of mercury in the tube adapted upon tilting of the tube to make and break an electric circuit including said electrical contacts, the baffle being adapted to trap a portion of the body of mercury when the tube is tilted to one of its positions, and an elongated tapering nozzle extending from adjacent the periphery of the baffle into one end of the tube, said nozzle forming a passage from one side of the baffle to the other for mercury trapped by the baffle when the tube is tilted to one of its positions, said nozzle terminating at its distal end in a restricted orifice, the mercury in the tube completely filling the nozzle and submerging the restricted orifice at all times, regardless of whether the tube is in its "on" or "off" position.

4. A delayed-action mercury switch comprising a tube adapted to be tilted to "on" and "off" positions, a baffle in said tube intermediate the length thereof, a pair of electrical contacts in the tube at one side of said baffle, a body of mercury in the tube adapted upon tilting of the tube to make and break an electric circuit including said electrical contacts, the baffle being adapted to trap a portion of the body of mercury when the tube is tilted to one of its positions, and an elongated tapering nozzle extending from the baffle adjacent the periphery thereof into one end of the tube, said nozzle forming a passage from one side of the baffle to the other for mercury trapped by the

baffle when the tube is tilted to one of its positions, said nozzle terminating at its distal end in a restricted orifice, the electrical contacts being in the end of the tube at the side of the baffle opposite that end into which the nozzle extends, so that there is a time delay between the tilting of the tube to the "off" position and the time the mercury ceases to bridge the electrical contacts, the mercury in the tube completely filling the nozzle and submerging the restricted orifice at all times, regardless of whether the tube is in its "on" or "off" position.

5. A delayed-action mercury switch comprising a tube adapted to be tilted to "on" and "off" positions, a baffle in said tube intermediate the length thereof, a pair of electrical contacts in the tube at one side of said baffle, a body of mercury in the tube adapted upon tilting of the tube to make and break an electric circuit including said electrical contacts, the baffle being adapted to trap a portion of the body of mercury when the tube is tilted to one of its positions, and an elongated tapering nozzle extending from the baffle adjacent the periphery thereof into one end of the tube, said nozzle forming a passage from one side of the baffle to the other for mercury trapped by the baffle when the tube is tilted to one of its positions, said nozzle terminating at its distal end in a restricted orifice, the electrical contacts being in the end of the tube into which the nozzle extends and in different horizontal planes so that there is a time delay between the tilting of the switch to the "on" position and the bridging of the contacts by the mercury, the mercury in the tube completely filling the nozzle and submerging the restricted orifice at all times, regardless of whether the tube is in its "on" or "off" position.

ROBERT WARREN ALLISON.
